UNITED STATES PATENT OFFICE.

CHARLES A. SCHRANZ, OF PHILADELPHIA, PENNSYLVANIA, ASSIGNOR TO WALTER WOOD, TRADING AS R. D. WOOD & COMPANY, OF PHILADELPHIA, PENNSYLVANIA.

COAL FEEDER FOR GAS PRODUCERS.

Application filed April 14, 1922. Serial No. 552,803.

To all whom it may concern:

Be it known that I, CHARLES A. SCHRANZ, a citizen of the United States, residing in Philadelphia, Pennsylvania, have invented certain improvements in Coal Feeders for Gas Producers, of which the following is a specification.

One object of my invention is to improve the construction of coal feeders for gas producers so as to prevent the clogging of the rotating feeding drum and to relieve the drum of the weight of the column of coal in the hopper.

A further object of the invention is to make the ends of the drum integral with the vanes and to locate the ends in the housing and also to provide separate bearings for the shaft on which the drum is mounted.

A still further object of the invention is to provide means for spraying water onto the drum by means of atomizers so as to produce a water fog in the compartments of the drum and seal the clearance space between the drum and the housing, preventing the escape of gas from the producer into the feed spout, or hopper.

In the accompanying drawings:

Fig. 1 is a sectional elevation of my improved coal feeder for gas producers on the line 1-1, Fig. 2;

Fig. 2 is a transverse sectional view on the line 2-2, Fig. 1; and

Fig. 3 is a sectional view illustrating a modification of the drum.

1 is the gas producer having an opening 2 through which coal is fed onto the fuel bed of the producer. 3 is the housing of a feeding apparatus having openings at each end. Secured to the outside of the housing at each end are bearing plates 4 in which the transverse shaft 5 is mounted.

On one end of the shaft 5 is a gear wheel 5^a, which may mesh with any suitable driving gear. On the opposite end is a hub 5^b, by which the shaft may be turned by hand.

6 is the feeding drum, which is secured to the shaft 5. This drum is preferably made of an integral casing having a hub 7, ends 8, and vanes 9, forming compartments 10 for the coal. The ends 8 are located in the openings 3^a in the housing. In the present instance, the drum has five vanes 9, but the vanes may be increased or de-

creased in number, depending somewhat on the design of the feeder. In some instances, the drum may be made in the form of a shell 6^a, having a single compartment 10^a and a single opening in the compartment, as shown in Fig. 3.

In the periphery of each end 8 of the drum are grooves 11 for water, which flows from a passage 12 into the grooves, and forms a water seal between the feeding drum and the housing. The water is supplied through a pipe 12, which has a suitable valve, as shown in Fig. 2.

The housing 3 is extended at one side, as at 13. Attached to this portion of the housing is a chute 14 arranged, in the present instance, to receive coal from a hopper 15. The bottom 16 of the chute is substantially on a line with the center line of the shaft 5 and is preferably flat and the portion 17 of the housing forms a continuation of the bottom portion. The weight of the column of coal is taken by the bottom portion 16 of the chute, relieving the drum of all unnecessary weight.

18 is a vertically adjustable gate located between the housing and the chute. In the present instance, the gate is held in the position to which it is adjusted by a bolt 19 adapted to one of a series of holes 20 in the gate. The construction of the gate and the retaining means may be modified, as desired.

In the upper portion of the housing above the drum is a space 18^a and a pivoted door 21 is so located that, when it is opened, the flow of coal may be watched, and, if a lump becomes jammed in the drum, it can readily be removed.

It will be noticed the feeder is so proportioned that the coal will flow by gravity from the chute to the drum and there will be no avalanching and over loading of the compartments of the drum. As the space 18^a in the upper portion of the housing 3 is empty, the edges of the vanes can readily cut through the fuel; and, as an upper cut is made, the coal is displaced rather than crushed. Thus, the grinding, or crushing, of the coal, or other fuel, between the edges of the vanes and the housing is prevented.

At the outer end of each vane 9 of the drum is a flange 22 projecting part way of the circumference of the drum, as shown in

Fig. 1. As the drum rotates in the direction of the arrow, Fig. 1, the flanges 22 prevent the compartments 10, between the vanes of the drum, from being completely filled with coal. The coal, as the drum revolves, will settle below the peripheral line of the drum and jamming of the coal between the drum and the housing is prevented. It will be observed that the wall at the left hand side of the space 13^a is located near the vertical plane of the axis of the drum. The location of this wall approximately as shown is important. If the wall were located close to the chute there would not be opportunity for the coal to settle below the peripheral line of the drum before the rear vanes of the respective pockets pass under the bottom edge of the said wall; and if the wall were located in a position at the extreme left the coal would begin to roll out of the pockets before the said rear vanes thereof passed under the lower edge of the wall.

When the drum discharges the coal into the producer, the flanges on the vanes retard the flow of the coal, therefore, it is more uniformly distributed over the fuel bed.

The drum can be rotated at varying speeds to control the flow of coal to the producer and the flow of fuel from the chute can be regulated by the gate.

At 23 are a series of ports in the housing. In these ports are water spray nozzles 24 of any suitable construction. The ports 23 are located directly under the flat portion 17 of the housing. A series of spray ports 25 is preferably arranged in the housing above the drum and water spray nozzles 26 are located in the ports, as shown. The nozzles project sprays of water into the compartments as they are presented on the rotation of the drum 6, forming a water fog, which will seal, to a large extent, the clearance space between the vanes of the drum and the housing, as the water, being finely divided, will moisten uniformly the entire surface of the machined portions of the housing. The water vapor will also weight down any gas that escapes past the drum and will prevent it from entering the chute, or the space above the drum.

I claim:

1. The combination in a coal feeder for gas producers, of a housing; a drum mounted in the housing capable of being rotated; and a chute at one side of the housing having an opening in its side to allow the coal to flow from the chute into the drum, the chute having a flat bottom which sustains the weight of the coal in the chute.

2. The combination of a housing; a drum mounted therein capable of being rotated; a chute at one side of the housing, said chute being open at one side to allow the coal to flow from the chute into the drum; and an

adjustable gate for controlling the flow of coal, the bottom of the chute sustaining the weight of coal in the chute.

3. The combination in a coal feeder for gas producers, of a drum rotatable about a horizontal axis and having feeding compartments therein, a housing enclosing the drum and having a discharge outlet with which the drum communicates at the bottom, the said housing also having an unobstructed chamber with which the drum communicates at the top, a chute at one side of the said chamber over which coal flows by gravity to the drum, a wall at the opposite side of the said chamber near the vertical plane of the axis of the drum, a supply hopper for the chute having one wall so located with respect to the drum that the upper surface of the layer of coal extending from the hopper along the chute will be at the natural angle of flow or repose and will extend to a line of intersection with the drum, the said surface being separated from any part of the feeder, means for rotating the drum in the direction to move the feeding pockets upward past the said layer of coal, and rearward extending flanges at the forward outer corners of the several feeding compartments for preventing the complete filling of the pockets.

4. The combination of a housing; a drum mounted in the housing, said drum having vanes forming compartments; a shaft on which the drum is mounted; bearings for the shaft, the vanes having flanges at the periphery of the drum extending in a direction opposite to the rotation of the drum; and a chute secured to one side of the housing, the side next to the drum having an opening so that the bottom of the chute, which is substantially on a line with the center line of the shaft, will allow coal to flow into the compartments of the drum formed by the vanes when a compartment is at one side of the shaft, the flanges on the vanes, at the periphery of the drum, preventing the complete filling of the compartments.

5. The combination in a coal feeder for gas producers, of a rotatable drum with feeding pockets therein, a housing enclosing the drum and having a feed opening at the top and a discharge opening at the bottom, means for feeding fuel to the drum through the feed opening, and two series of water spray pipes extending longitudinally of the drum and located at opposite sides thereof, each series of spray pipes being located between the feeding and discharge openings and serving not only to moisten the fuel but also to prevent leakage of gas from the discharge opening to the feed opening.

6. The combination of a housing having an opening at each end and having an ex-

tension at one side provided with a flat bottom; a chute secured to the extension and having a bottom forming a continuation of the bottom of the extension of the housing; 5 a drum having compartments and also having solid ends that are located in the openings in the housing, said chute having an opening to allow coal to flow by gravity into the compartments of the drum, the housing having an open space directly above that portion of the drum next to the chute; and 10 a door closing the opening.

7. The combination of a housing having

an opening; bearings on the outside of the housing at each end; a shaft mounted in the 15 bearings; a drum mounted on the shaft between the bearings, said drum having vanes and solid ends, the ends extending into the openings in the housing; one or more annular grooves in the periphery of the ends 20 of the drum; passages in the housing communicating with the grooves; and means for allowing water to flow through the passages into the grooves to form a water seal to prevent the escape of gas.

CHARLES A. SCHRANZ,
